UNITED STATES PATENT OFFICE.

CHARLES M. GREEN, OF MARBLEHEAD, MASSACHUSETTS, ASSIGNOR TO THE WALTER M. LOWNEY COMPANY, OF BOSTON, MASSACHUSETTS, A CORPORATION OF MASSACHUSETTS.

DIPPING-MACHINE.

1,128,308.

Specification of Letters Patent. Patented Feb. 16, 1915.

Application filed January 13, 1913. Serial No. 741,629.

To all whom it may concern:

Be it known that I, CHARLES M. GREEN, of Marblehead, county of Essex, and State of Massachusetts, have invented a new and 5 useful Improvement in Dipping-Machines, of which the following is a specification.

My invention is particularly useful in the making of chocolate bonbons, where centers are usually dipped by hand into melted 10 chocolate and are thus coated. My invention however may be used for dipping other articles if desired.

In machines for dipping centers heretofore constructed two difficulties have been 15 experienced, the first being the maintaining of the chocolate with which the centers are to be coated, at a proper consistency and free from air bubbles, and the other the handling of the centers themselves both before 20 and after they have been dipped.

My invention relates to improvements in both of these means, and it will be understood from the drawings in which the best embodiment of my invention now known to 25 me is shown.

Figure 1 is an elevation of a machine embodying my invention, the supporting frame being omitted. Fig. 2 is a vertical section, the power shaft and its connection being 30 omitted. Fig. 3 is an enlarged section on line 3—3 of Fig. 2. Figs. 4 and 5 are respectively an under and side view of the cam disk. Fig. 6 is an enlarged section on line 6—6 of Fig. 1. Fig. 6^a is a section showing 35 the air pump connection. Fig. 7 is a top view, and Fig. 8 a side view, both full size, of the center-holding means or finger mechanism. Fig. 9 is a section on line 9—9 of Fig. 7. Fig. 10 is a section on line 10—10 40 of Fig. 9.

The mechanism for maintaining the chocolate at proper consistency may be utilized for other like purposes, and comprises a tank A which is provided with a 45 water jacket A¹. Within the water jacket may be introduced hot water or steam according to the temperature desired, which is kept in constant circulation by means of pipes a a¹ in the usual way. This water jacket surrounds the periphery of the tank A and extends under its bottom, so that the

bottom and side walls of the tank A are kept at the proper temperature.

The dipping process takes place in a pan B which is supported by a water jacket B² 55 carried by suitable supports c from the frame C, which in turn is mounted on the tank A, as will be more particularly described below. The pan B has a downwardly projecting neck B¹ which extends 60 into and forms a passage from the tank A for the chocolate. The water jacket B² is below the pan and surrounds its neck, and steam and hot water may be circulated through it by means of pipes b b¹ in order 65 to maintain the contents of the pan B at a proper temperature. Within the neck or extension B¹ of the pan I mount a conveyer D. This conveyer comprises a cylinder resting on a hub c² and attached to the upper 70 end of a sleeve d which sleeve passes down through a stuffing box a² in the chamber between the water jacket A¹ and tank A, and to the sleeve is keyed a beveled gear d¹ which is engaged by a beveled gear d² 75 mounted on the end of the shaft d³, carrying at its farther end a bevel gear d⁴. This beveled gear d⁴ is in mesh with a beveled gear d⁵ on the lower end of a vertical shaft d⁶, carrying at its upper end a beveled gear 80 d⁷ which meshes with a beveled gear d⁸ on the end of the power shaft C¹ carrying a pulley C². These various shafts are mounted in bearings supported either on the frame C or jacket A¹, as the case may be, and by 85 means of power applied to the pulley C² the cylinder D is rotated. The cylinder D is somewhat smaller in diameter than the extension B¹ of the pan B, so that a passage 90 is left between the exterior of the cylinder D and the interior wall of the extension B¹. Near the lower end of the cylinder D and on the outside thereof there is a spiral conveyer D¹ extending two or three turns about the cylinder D. This conveyer being of sufficient width to substantially close the lower end of the passage formed between the outer wall of the cylinder D and the inner wall of 95 the extension B¹.

The water jacket chambers being filled 100 with hot water or steam to maintain the contents of the tank and pan at proper tem-

perature, and the tank A being substantially filled with chocolate or other like material which is about to be lifted to the pan B, the cylinder D is rotated in such a direction 5 that the lower end of the spiral conveyer D¹ will move into the chocolate and cause the chocolate to travel up the conveyer into the chamber between the cylinder and the interior of the extension and gradually to be 10 lifted or conveyed up into the pan B. In practice it is desirable that this lifting process shall convey to the pan the chocolate in greater quantities than is needed. It will be noticed that the pan B is of less diameter 15 than the tank A, and if the tank receives more chocolate than can be used chocolate will overflow all around from the pan B and fall back into the tank A. Thus there will be a constant circulation of chocolate 20 through the apparatus, and the chocolate will have no opportunity to settle or thicken, and because of this constant mixing or agitation the entire mass will be maintained at substantially the same condition.

25 To insure the maintenance of an even temperature in the chamber between the cylinder D and outer wall of B¹ I have not only provided a chamber between the wall of B¹ and the jacket B², but I have also provided means for maintaining the cylinder D at proper temperature, these means comprising an inlet pipe d⁹ which is extended up within the sleeve d, and also an outlet d¹⁰ which conveys away the exhaust or waste 30 from the lower end of the cylinder through a passage between the interior of the sleeve d and the exterior of the inlet d⁹. It will be noted that the lower end of the sleeve d is mounted in a stuffing box bearing d¹¹ on top 35 of the exhaust casing d¹³ supported from the underside of the jacket A¹ by means of brackets d¹². Thus the sleeve and the cylinder D mounted upon it may be rotated independently of the casing d¹³ from which the 40 outlet d¹⁰ leads.

45 The jacket B² and neck B¹ should have a water tight joint where they join below and for this purpose I prefer that each should have a lateral extension, which should overlap 50 lap as shown at b² in Fig. 2.

I have also shown an agitator to assist in keeping the chocolate in proper condition. It comprises the hub c² resting on the bottom of the tank A and adapted to turn about 55 the sleeve d. From this hub project horizontal arms e¹ having upturned ends e³ and also having vertical arms e which connect it with the gear E. The gear E surrounds an asbestos casing E¹ which is outside of the 60 jacket B² and which serves as a heat insulator. To rotate this agitator the gear E is in mesh with a gear E² mounted on a stud E³ supported on the tank A and in mesh with a pinion E⁴ mounted on the hub of the

shaft d⁶. Thus upon the rotation of the conveyor or lifter D D¹, the agitator is also rotated so that the entire mass is kept in constant agitation, both while in the tank A and during its lifting and overflowing processes, and by virtue of the various 70 chambers around the various parts, with their various inlets and outlets, the temperature of the chocolate is maintained constantly at any desired degree.

75 The center dipping mechanism is mounted upon a rotary head supported in the frame C over and concentric with the pan B. During the dipping operation the centers are held by fingers of which two sets only are shown, but it is intended that the machine shall be provided with such a number of fingers as may be convenient according to the size of the machine. In the drawings the fingers are located at nearly opposite sides of the machine, and the arrangement is such that during one rotation of the head each set of fingers will go twice through the operations of grasping a center and dipping and releasing it, the mechanism for operating the fingers being duplicated 80 on the head. In a smaller machine this process might take place but once, while in a larger machine the mechanism might be triplicated, etc., according to circumstances.

85 The head itself comprises a stationary 90 part and a movable part. The movable part consists of a disk F which is mounted on the lower end of a sleeve F¹, the upper end of which carries a beveled gear F². The sleeve F¹ has a series of openings f equaling 100 in number the number of sets of center gripping fingers. And from each opening leads a tube f¹ the mouth of which terminates just over one of the sets of fingers. Within this sleeve is a tube F³ which passes up 105 through a bearing C¹⁰ in the frame C and is made fast by a nut f² and set nut f³. This tube F³ is stationary and has in it two openings f⁴ in position to register with each opening f as the sleeve rotates, and the upper end of this sleeve is similarly connected 110 with a blower C³ so that a blast of air is constantly passing into the tube F³ and out through whichever of the openings f happens to register with the openings f⁴. Within this tube F³ is an inner tube F⁵ through which electric wires l² pass down to the rotary portion of the head for purposes below 115 described. The beveled gear F², by means of which rotation is given to the rotary head, meshes with the beveled gear F⁶ on the shaft F⁷, supported by hangers F⁸ carried by the frame C and having a gear F⁹ in mesh with the pinion F¹⁰ on the end of the shaft F¹¹ carrying suitable pulley connections so that the rotation of the shaft F¹¹ will cause the rotation of the rotary head.

120 The stationary head G is supported upon

brackets G^1 and from it depends a cam disk H which will be described below.

The rotary head carries hinged to its periphery a series of fingers J . These fingers 5 are shown in detail in Figs. 7, 8, 9 and 10, and are constructed as follows: Each grasping and dipping unit comprises three fingers j, j^1, j^2 . The outer ends of the fingers j and j^2 are alike, each comprising prongs j^3 and a 10 screw j^4 . The fingers j^1 are shown loop shape at the end, as at j^5 , and aid in finishing the coating as described below. The fingers j and j^2 fit into the sides of the centers, the steadyng pins j^4 being adjustable 15 according to the general style of the centers being covered. I prefer to make the end j^5 of the finger j^1 easily removable so that it may be changed if desired. This finger is also provided with a pin J^1 for purposes below described. These fingers must be given 20 proper movements in order that they may open and receive the center and may close again about the center and hold the center during the dipping operation and afterward at the proper time release it. The opening and closing operation is due primarily to the way in which the fingers are mounted, and, secondarily, to certain mechanism brought to bear upon the fingers for 25 this purpose. Each finger j, j^2 is mounted on the end of a lever k, k^2 which is pivoted at k^3, k^4 in a cylindrical block K^{11} mounted to turn in a holder K . This holder K is hinged to a plate K^1 carried by the rotary 30 head F and is normally held in nearly horizontal position by the spring k^8 , one end of which is connected to the plate K^1 and the other to the holder K . In the rear end of the block K^{11} slides a button K^2 which is 35 suitably centered so as to move directly in and out therefrom and is slotted as at K^3 . Within this button are two pins K^4 which pass through slots k^5, k^6 in the rear ends of the levers k, k^2 . As a result it will be seen 40 that the compression of the button against the block will cause the opening or spreading of the fingers j, j^2 (see Fig. 7). The finger j^1 is also pivoted in the block K^{11} at k^7 , and held normally in its lower position 45 by means of a spring k^8 . When the parts are in the position shown in Fig. 7, the fingers j, j^2 are held against accidental separation, which would result in the dropping of the center. The holder K also carries an 50 electric heater L of ordinary construction, which need not be described, as any electric heater will answer the purpose. Current is brought to it by means of wires L, J^1 which are connected with the wires J^2 in the tube F^3 . The upper end of this tube is provided 55 with suitable connections J^3 , and the parts are insulated in a way which will be readily understood.

The cam disk referred to above is con-

nected with the stationary portion G of the 65 head as shown in side elevation in Fig. 5, Fig. 4 showing an under view of the cam disk. The purpose of this cam disk is to give the necessary movements to the fingers j, j^1, j^2 as well as to the holder K by which 70 all these parts are carried. For this purpose the holder is provided with a lever K^6 fulcrumed on the button K^2 , the lower end of which lever is loosely attached to the arm K^7 by means of which the holder K is pivoted to the part K^1 on the disk F . The cam disk G is provided a set of cam surfaces G^1 to engage the pins K^5 , and another set of surfaces G^2 to engage the levers K^6 . A third set, G^3 , is also provided to engage the pin J^1 (see Fig. 11). As has been stated above, the cam surfaces are repeated so that the holders will dip two centers during one rotation of the rotary head. In addition the block K^{11} is given a partial rotation while 85 the center is in the chocolate, its rotation being completed later. For this purpose the block K^{11} is provided with a gear K^8 fast thereto, and the cam disk G is provided with racks K^9, K^{10} to engage and turn the gear as 90 occasion requires.

In describing the movements of the holder and the various parts connected thereto, I shall describe the movement of each part separately for the sake of clearness, and then 95 briefly describe how these various parts co-operate for the purpose for which they are designed.

The holder K with its various parts must be given a vertical oscillation in order that 100 it may grasp the center which is fed to it at a level above the level of the top of the pan E and then lower the center into the pan and turn it therein to coat it thoroughly, and thereafter lift it from the pan and give 105 it a shaking to shake off the superfluous chocolate, and then lower it to place it upon a proper receptacle, after which the operation is repeated.

The cam surface to engage the pin K^5 110 which may be termed the level-controlling pin, is partially an edge cam and partly a groove of irregular shape, and the movements given to the holder by this cam are around the pivot by which it is hinged to 115 the plate K^1 . The operation begins at approximately the point marked "x" (see Fig. 4), where it will be noted that the surface of the cam G^1 marked 1 to 2, is substantially an arc, and is such as to hold the fingers in their highest position. From 2 to 3 the surface against which the pin K^5 is held by the spring k^8 gradually moves outward until it reaches its point farthest from the center of the cam disk and from there to 120 the point 4 the surface is substantially an arc, and during this period the fingers are held in their lowest position, the center be-

ing dragged through the chocolate pan. From 4 to 5 the surface slopes back to substantially the radius of the cam disk, and from 5 to 6 it is serrated so that as the holder is moved along it is given a final jogging or shaking so that the superfluous chocolate is removed. From 6 to 7 the surface is again an arc to allow the rotation of the holder as below described, and at 7 the 10 pin K^5 enters an irregular groove which lifts the fingers sufficiently high to enable them to place the covered center upon a suitable receptacle, and during the slight drop allowed by the surface from 8 to 9 the covered 15 center is placed on the receptacle or plaque. From 9 to 1 it lifts the fingers again and the operation is repeated, the fingers receiving their next center between the points 1 and 2, as before. While the centers are being held in 20 the chocolate bath, that is, while the holder is being operated by the cam surface 3 to 4, it is desirable that they should be rotated somewhat so as to insure the complete covering of the center. For this purpose I provide 25 a rack surface K^9 which engages the gear K^8 . In the form of my invention shown the rack K^9 has four teeth and the gear has 8 teeth, so that the rack gives the holder half a revolution. After the shaking operation 30 takes place a further half revolution is given to the holder by means of the rack K^{10} , this bringing the covered center into position to be laid upon its bottom on the receptacle.

35 The cam surface G^2 engages the lever K^6 by means of which the fingers are opened and closed to release one covered center and to grasp a second center ready to be covered. For this purpose there is provided a surface 40 10 to 11 against which at the proper time the upper end of the lever K^6 strikes, and as the holder continues its movement the lever K^6 is gradually depressed so that the button K^2 is pushed inwardly toward 45 the holder and opens out the fingers j^1 , j^2 , causing them to drop or become disengaged from the covered center. They are then lifted by the cam G^1 so as to ride over the top of the center and then come down, and are 50 carried farther along the surface 12 to 13, when they are again suddenly opened by the surface 13 to 14 over a new center, and again closed along the surface 14 to 15, at which time the fingers begin their descent 55 toward the chocolate in the pan E , and the dipping operation goes on. In addition, however, the finger j^1 must also be lifted in order that it shall not bear on the center during the dipping operation and so prevent 60 the center from being entirely covered with chocolate, and later, just before the dipped center is placed on the plaque so that a finish shall be put on top of the chocolate, and for this purpose I have attached

to the cam disk a surface G^5 which engages 65 with the pin J^1 and lifts the finger j^1 against the force of the spring k^8 , and a second surface G^3 hanging from G^{11} for the same purpose. By this means a string of chocolate is drawn up from the top of the coating 70 until it breaks and falls back upon the coating, thus making an ornamental or finishing strip which is purely accidental in shape so that it forms a finish on top of the chocolate in substantially the same way that each 75 hand-dipped bonbon is at present finished. During all this time the heaters L on the holders are kept sufficiently hot electrically to warm the fingers, so that the coating is maintained at a temperature similar to that 80 usual during hand dipping. The air blast openings f and f^4 register at such times as to allow a blast of air,—the temperature of which may be regulated if desired, to strike the covered center an instant before it is 85 dropped, as will be understood from Fig. 6.

It will be understood that in such a machine as is shown in the drawings when two sets of coating operations are going on at the same time, there should be two sets of 90 parts to feed centers to the coating mechanism and receive them when coated, located opposite each other.

The advantage of the chocolate lifting mechanism shown is due to the fact that 95 friction is largely eliminated, and the temperature of the chocolate can be maintained at a predetermined degree. Moreover, there is no tendency for air bubbles to collect in the chocolate—in fact there is no opportunity for air to collect in the chocolate on the lifter. The chocolate is thus lifted in a continuous solid stream of given temperature, which, so far as I know, is not the case when chocolate is lifted by any of the pumps 100 in use. This mechanism while described as a chocolate lifter, may be used for other liquids, especially those of a similar character.

While the end of the finger j^1 is shown as 110 loop shaped it may be otherwise shaped, for example, like a star or a fork, or otherwise, and so change somewhat the finish of the goods. This finish will in any event be irregular and resemble the irregular finish 115 on hand-dipped goods.

While I have described this machine with considerable particularity, I do not mean to limit myself to the particular construction shown, as many alterations in the details of construction will doubtless occur to one skilled in the art which will not depart from the spirit of my invention.

What I claim as my invention is:—

1. In a machine of the kind described, a 125 tank, a pan mounted concentrically therewith above said tank and having a downward extension into said tank, and a lifter

- located in said extension near the bottom thereof adapted to lift the contents of said tank into said pan.
2. In a machine of the kind described, a tank, a pan mounted concentrically above said tank and having an extension downward into said tank, and a lifter located in said extension and adapted to lift the contents of said tank into said pan, said pan being of less diameter than said tank, whereby any excess in the amount of material lifted will overflow the edges thereof and fall back into said tank.
3. In a machine of the kind described, a tank, a pan located above said tank and having a cylindrical downward extension into said tank, and a lifter located in said extension and comprising a spiral conveyer and rotary means for supporting it and means for controlling the temperature of said conveyer whereby the material lifted will be maintained at a constant temperature in its passage from the tank to the pan.
4. In a machine of the kind described, a tank, a pan located above said tank and having a cylindrical downward extension communicating with the contents of said tank, a rotary cylinder located within said extension, a spiral conveyer mounted on the periphery of said cylinder and having a diameter sufficient to engage the inner wall of said extension.
5. In a machine of the kind described, a tank, a pan located above said tank and having a cylindrical downward extension communicating with the contents of said tank, a rotary cylinder located within said extension and extending downward into the contents of said tank, a spiral conveyer mounted on the periphery of said cylinder extending a short distance upward from the lower end thereof and having a diameter sufficient to engage the inner wall of said extension.
6. In a machine of the kind described, a tank, a pan located above said tank and having a cylindrical downward extension communicating with the contents of said tank, a rotary cylinder located within said extension and extending downward into the contents of said tank, a spiral conveyer mounted on the periphery of said cylinder extending a short distance upward from the lower end thereof and having a diameter sufficient to engage the inner wall of said extension, in combination with jacketing means for said pan and said tank, whereby they may be kept at a constant temperature.
7. In a machine of the kind described, a tank, a pan located above said tank and having a cylindrical downward extension communicating with the contents of said tank, a rotary cylinder located within said extension and extending downward into the contents of said tank, a spiral conveyer mounted on the periphery of said cylinder extending a short distance upward from the lower end thereof and having a diameter sufficient to engage the inner wall of said extension.
8. In a machine of the kind described, a tank, a pan of less dimensions than said tank, located above said tank and within the projected walls thereof and concentrically therewith, centrally-located means for lifting the contents of said tank to said pan whereby said lifted contents will be distributed substantially equally over the surface of said pan and any excess of material will overflow the edges of said pan into said tank, and means located in said tank to keep its contents in constant agitation, the base of said pan, said tank and said lifting means being jacketed, suitable connections being provided therewith whereby said jacket may be maintained at a constant temperature.
9. In a machine of the kind described, a pan, a stationary head located over said pan, a rotary head located between said stationary head and said pan, one or more sets of grippers located on said rotary head, means for rotating said rotary head comprising a hollow shaft having lateral openings therein equal in number to the number of said grippers, a series of tubes each leading from one of said openings to a point above one of said grippers, an inturned hollow bearing for said shaft having lateral openings equal in number to the number of sets of grippers and each adapted to register with each of the hollow openings in said hollow shaft in turn, and means for supplying an air blast to said hollow bearing.
10. In a machine of the kind described, a receptacle adapted to hold coating material and means for dipping centers therein comprising two oppositely-disposed arms, each arm having prongs, said prongs being oppositely disposed and means for moving said arms toward each other whereby a center will be gripped between said oppositely disposed prongs, means for dipping said center while so gripped into said coating material, and means for separating said arms to release said center after it has been coated.
11. In a machine of the kind described, a gripper comprising two oppositely disposed arms and means for moving them toward and from each other, each arm having prongs adapted to engage and grip a center, and a screw located between said prongs adapted to be adjusted according to the size and shape of the center to be dipped.
12. In a machine of the kind described, a plurality of center-holding and dipping

means, and individual heating means attached to each center-holding and dipping means.

13. In a machine of the kind described, a gripper comprising a holder, arms pivoted thereto and slotted at their rear ends, and a button adapted to slide in and out from said holder and having pins adapted to engage said slots, whereby upon the movement of said button said arms will be moved toward or from each other.

14. In a machine of the kind described, a gripper comprising a holder, arms pivoted thereto and slotted at their rear ends, and a button adapted to slide in and out from said holder and having pins adapted to engage said slots, whereby upon the movement of said button said arms will be moved toward or from each other, in combination with means adapted to engage and move said button.

15. In a machine of the kind described, a gripper comprising a holder, arms pivoted thereto and slotted at their rear ends, and a button adapted to slide in and out from said holder and having pins adapted to engage said slots, whereby upon the movement of said button said arms will be moved toward or from each other, in combination with means adapted to engage and move said button comprising a lever located on said button and a cam surface adapted to engage said lever and means adapted to bring said lever and said cam surface into engagement.

16. In a machine of the kind described, a tank, a pan of less dimensions than said tank and located above said tank and within the projected walls thereof and concentrically therewith, said pan having side walls to maintain a predetermined depth of liquid material fed thereto, centrally-located means for lifting the contents of said tank to said pan whereby said lifted contents will be distributed substantially equally over the surface of said pan and any excess of material will overflow the sides of said pan into said tank, the base of said pan, said tank and said lifting means being jacketed, in combination with connections whereby said jacket may be maintained at a constant temperature as desired.

17. In a machine of the kind described, a tank, a pan of less dimensions than said tank and located above said tank and within the projected walls thereof and concentrically therewith, said pan having side walls to maintain a predetermined depth of liquid material fed thereto, centrally-located means for lifting the contents of said tank to said pan whereby said lifted contents will be distributed substantially equally over the surface of said pan and any excess of ma-

terial will overflow the sides of said pan into said tank, in combination with means whereby articles may be submerged in the contents of said pan.

18. In a machine of the kind described, a gripper comprising a holder, arms pivoted thereto and slotted at their rear ends, and a button adapted to slide in and out from said holder and having pins adapted to engage said slots, whereby upon the movement of said button said arms will be moved toward or from each other, in combination with a stationary head having a cam surface and a rotary head, said gripper being mounted on said rotary head and having a lever mounted on said button adapted to engage with said cam surface whereby said lever will be operated and said button will be depressed.

19. In a machine of the kind described, a gripper having three arms mounted thereon, two of said arms being opposite each other and adapted to engage the sides of a center and the third arm being adapted to engage the top of the center, and means whereby said first named arms may be opened to receive and also to release a center and means whereby the third arm may be moved independently of the other two.

20. In a machine of the kind described, a gripper having three arms mounted thereon, two of said arms being opposite each other and adapted to engage the sides of a center and the third arm being adapted to engage the top of the center, and means whereby said top engaging arm may be lifted off said center during the dipping operation and while said center is still held by the other arms.

21. In a machine of the kind described, a gripper having three arms mounted thereon, two of said arms being opposite each other and adapted to engage the sides of a center and the third arm being adapted to engage the top of the center, the outer end of said top-engaging arm being loop-shaped as and for the purposes set forth.

22. In a coating mechanism, a pan, a gripper mechanism located over said pan and comprising a pair of gripping fingers and a finishing finger, means whereby said gripper mechanism is normally held in substantially horizontal position, means for separating said fingers while in said position and for closing them together, means thereafter operable to rock said gripper mechanism vertically into and out from said pan, and means whereby said finishing finger is lifted from proximity to said gripping fingers operable after said gripper mechanism has been rocked into and out of said pan and while said gripping fingers are in holding position, whereby said finishing finger

will lift a portion of the coating of the article held by said gripping fingers and allow it to fall on said article.

28. In a machine of the kind described, gripping mechanism comprising a plurality of fingers adapted to grip an article and a finishing finger adapted to coöperate with said gripping fingers in holding the article

and having a broadened end adapted to draw up and then drop a string of chocolate in 10 the finishing operation.
